VIBRATORY MASSAGE CUSHION

Murlyn J. Eiden, Silver Creek, N.Y., assignor to Niagara Therapy Manufacturing Corporation, Adamsville, Pa., a corporation of Delaware

Filed May 18, 1959, Ser. No. 813,864

9 Claims. (Cl. 128—33)

This invention relates to therapeutic massage units and more particularly to a therapeutic massage unit which presents a relatively flat cushion section and a roll section, which together provide a pad, cushion, mattress or mattress pad designed to transmit deep and penetrating massage action to a part or the entire human body reclining there-against.

The cushion section of the therapeutic massage unit constructed in accordance with this invention contains one or more motion transmitting members compactly sandwiched between a pair of highly resilient cushioning slabs. The roll section contains one or more housing shells, each detachably connected to the adjacent end of one of the motion transmitting members, and is covered by a highly resilient and arcuately shaped cushioning slab in embracing relation thereto. Each housing shell is made from flexible sheet material and presents a semi-tubular body portion designed to contain and support a gyratory motor assembly which can be removed through the outer end of the housing shell when the housing shell is partially detached from its motion transmitting member. The cushion section and roll section are snugly contained within a snug fitting covering envelope having an openable slit through which convenient access may be had to the wiring connections to the motor assemblies and to the means for detachably securing each housing shell to its motion transmitting member so that the motor assemblies can be quickly and easily removed and replaced in the field by unskilled labor.

The semi-tubular body portion of each housing shell presents a pair of flange portions extending laterally therefrom by means of which the housing shell may be detachably secured to one end of the motion transmitting member as contained in the cushion section of the unit. This invention features improved means for detachably securing the flange portions of the housing shell to its motion transmitting member and which may be readily manipulated from one side of the unit to effectuate expansion or contraction of the flexible tubular body portion of the housing shell. When the securing means are manipulated to permit expansion of the tubular body portion of the housing shell, the motor assembly contained therein may be readily removed from one end thereof, and when the securing means are manipulated to contract the semi-tubular body portion of the housing shell snugly around the body of the motor assembly, the motor assembly is thereby firmly held in supported position therein. The outer end of each housing shell is closed by a closure cup having air circulation holes in the end wall thereof and which is rigidly held in mounted position when the tubular body portion of the shell is contracted, and can be readily removed when the semi-tubular body portion is expanded, by appropriate manipulation of the means which secure the housing shell to its motion transmitting member.

Each motor assembly as removably contained within its housing shell comprises a variable speed gyratory motor which operates on either direct or alternating current and whose rotor shaft is supported by permanently lubricated and self-aligning bearings mounted in the end walls of the stator casing. An air circulation fan is fixed to one or both projecting ends of the motor shaft. Motor unbalancing counter-weights are also fixed to one or both ends of the rotor shaft, which produce a rotor unbalance

2

well in excess of any unbalance due to inaccuracies of manufacture, and which causes the motor casing to describe an elliptical path of motion which is transmitted through the housing shell to the vibration transmitting member and resilient cushioning slabs of the cushion section and roll section.

This invention further features the provision of a wiring circuit supported by a relatively thin panel formed of compressed fibres or the like which is a non-conductor for electricity, and which seats flatly against the motion transmitting member or members as sandwiched between the resilient cushioning slabs of the cushion section, and is positioned adjacent the flange portions of the housing shell. The motor lead wires and the panel supported wiring circuit are provided with complementary connector sockets and insert prongs which may be readily connected and disconnected to thereby permit convenient removal of the motor assembly or assemblies as contained within the roll section of the unit. The panel supported wiring circuit is connected to a power input cable which contains the ground wire and live wires which supply the operating current to the stator and rotor windings of the motor assembly or assemblies.

This invention further features a covering envelope made from strong and non-stretchable material such as a textile, or natural or artificial leather, or plastic covering material, which presents a sleeve forming leg portion, formed by a pair of facing panels connected along the side edges and one end edge thereof, and designed to be snugly drawn over the resilient cushioning slabs of the cushion section in a manner to maintain these cushioning slabs under slight compression and in firm motion-transmitting engagement with the motion transmitting member or members sandwiched therebetween. The covering envelope also includes a hood portion which presents an arcuate shaped panel which may be stitched to or formed integral with one of the facing panels of the sleeve portion. A pair of semi-circular end panels stitched to the arcuate shaped panel and each having a circular hole therein, are designed to partially cover the perforated end wall of the adjacent end closure cup of the roll section in a manner to permit free circulation of air therethrough.

The covering envelope of this invention further features the provision of a slide fastener designed to detachably connect the free edge of each semi-circular end panel and the free longitudinal edge of the arcuate panel of the hood portion thereof, to the free edges of the adjacent facing panel and side edge forming strips of the leg portion thereof. By an opening manipulation of the slide fastener, an open slit is formed between the hood portion and leg portion of the covering envelope, through which access may be readily had to the means which detachably secure the housing shell or shells to their respective vibration transmitting members, and also to the wiring circuit at the adjacent end of the cushion section so that the connector sockets and complementary insert plugs may be conveniently connected and disconnected. The above-described combination of features greatly facilitates the convenient removal of an inoperative or defective motor and the insertion of an operative replacement motor through the outer end of its housing shell. When the slide fastener is returned to closed position, the hood portion and leg portion are fully connected to provide a covering envelope which completely and snugly encloses the cushion section and roll section of the unit.

Where the therapeutic massage unit of this invention is to be made of sufficient length and width to fully support the entire length of the reclining body, the cushion section desirably contains a pair of motion transmitting members which have a combined area which is prefer-

ably only slightly less than the area of the cushioning slabs between which the motion transmitting members are sandwiched. Each motion transmitting member may be formed as a lattice or grid composed of relatively thin bands of spring steel or like resilient metal or plastic, and which includes a series of spaced longitudinally extending bands joined at the upper and lower ends thereof by transversely extending end bands. Where the therapeutic massage unit is made to provide a full length mattress or mattress pad, improved motion transmitting action over the full length of the mattress or mattress pad can best be attained by also connecting the longitudinally extending bands to a series of intermediate flexible bands which are inclined at an acute angle to the longitudinally extending bands.

Where two or more motion transmitting members or grids are provided, the adjacent side edges of the members or grids are preferably joined by flexible connecting straps which may be cut from a heavy belting material. Each motion transmitting member or grid is detachably connected to its own housing shell, and each housing shell contains a gyratory motor assembly. Thus, where two motion transmitting members are contained in the cushion section, the roll section contains a corresponding number of flexible housing shells, each containing a gyratory motor assembly. Where the therapeutic massage unit is formed of more limited length and width to support only a part of the human body reclining thereagainst, only a single motion transmitting member, a single housing shell and a single gyratory motor assembly are required.

Other objects and advantages of this invention will become apparent as the disclosure proceeds.

Although the characteristic features of this invention will be particularly pointed out in the claims, the invention itself, and the manner in which it may be made and used, may be better understood by referring to the following description taken in connection with the accompanying drawings forming a part hereof in which:

FIG. 1 is a plan view of a therapeutic massage unit made in accordance with this invention and comprising, a body supporting cushion section containing one or more motion transmitting members sandwiched between highly resilient cushioning slabs, and a roll section containing one or more gyratory motor assemblies each removably pocketed within a housing shell separably connected to one end of its motion transmitting member, certain parts being broken away to illustrate structural details;

FIG. 2 is a fragmentary side elevational view of the therapeutic massage unit shown in FIG. 1;

FIG. 3 is a fragmentary transverse section taken longitudinally of the therapeutic massage unit as the same would appear when viewed along line 3—3 of FIG. 1;

FIG. 4 is a longitudinal section of the therapeutic massage unit as the same would appear when viewed along line 4—4 of FIG. 3, this view revealing structural details of two vibration transmitting members contained in the cushion section, and also showing the manner in which the gyratory motor containing housing shells are arranged and detachably secured to their respective motion transmitting members;

FIG. 5 is a fragmentary longitudinal section of the therapeutic massage unit taken longitudinally of the roll section and showing a fragmentary part of the cushion section, this view revealing two gyratory motor assemblies as contained within and supported by their housing shells and the current supply circuits as separably connected to the motor lead wires;

FIG. 6 is a fragmentary perspective view of one of the expandable housing shells and the gyratory motor assembly removably positioned therein as viewed along line 6—6 of FIG. 5, this view also showing a fragmentary part of one of the motion transmitting members and the

associated means for detachably securing the same to the housing shell in exploded relation to the housing shell;

FIG. 7 is a transverse section of a fragmentary part of the roll section and cushion section of the unit and which reveals the manner in which the motor containing housing shell and motion transmitting member are secured together by the separable securing means;

FIG. 8 is a fragmentary plan view of the roll section and adjacent end of the cushion section, this view showing the manner in which the leg portion and hood portion of the covering envelope may be separated to provide a slit opening between the roll section and cushion section whereby access may be had to the wiring connections to the gyratory motors and to the means which detachably secure the motor containing housing shells to the motion transmitting members when the gyratory motor assembly is to be replaced;

FIG. 9 is a fragmentary transverse view of one end of the roll section and cushion section as the same would appear when viewed along line 9—9 of FIG. 4;

FIG. 10 is a fragmentary perspective view of the motion transmitting members, motor containing housing shells and adjacent current supply circuits, with the end closure cups exploded from the outer ends of the housing shells, and which illustrates the manner in which the gyratory motor assemblies can be disconnected from the wiring circuits, the motor assembly removed from the housing shell, and a replacement motor assembly substituted;

FIG. 11 is another fragmentary perspective view of the motion transmitting members, motor containing housing shells and adjacent current supply circuits, and which reveals modified means for securing and partially releasing the motor containing shell from its motion transmitting member to permit removal and replacement of the gyratory motor assembly;

FIG. 12 is a fragmentary perspective view of the motor containing housing shell, the adjacent motion transmitting member, and the modified securing means for detachably connecting the housing shell to the motion transmitting member as shown in FIG. 11, and as the same would appear in exploded relation; and

FIG. 13 is a fragmentary transverse view of the roll section and cushion section which reveals the housing shell and the adjacent motion transmitting member as detachably connected together by the modified securing means shown in FIGS. 11 and 12.

Similar reference characters refer to similar parts throughout the several views of the drawings and specification.

Therapeutic massage units made in accordance with this invention present a relatively flat and resilient cushion section C and a resilient and arcuate shaped roll section R at one end of the cushion section. The cushion section C may be made of any desired length and width to provide a massage mattress or mattress pad to support the entire length of the human body reclining thereon, or the cushion section C may be made of lesser length and width to support only a part of the body seated or reclining thereagainst. Elliptical massage strokes are delivered to the body supporting surface of the cushion section C and roll section R by one or more gyratory motor assemblies 10a and/or 10b contained within the roll section and which are operatively connected to corresponding motion transmitting members 1a and/or 1b contained within the cushion section.

In cases where the therapeutic massage unit is to provide massage coverage for only a part of the body reclining thereagainst, the cushion section C would have a length in the order of one and one-half to three feet and a width in the order of one and one-half to two feet, in which case only a single motion transmitting member 1a or 1b need be contained within the cushion section C, and which would be powered by only a single gyratory motor assembly 10 contained within the roll section R. However, where the therapeutic massage unit is of a size

to provide a massage mattress or mattress pad designed to be placed upon a bed mattress or on the floor or other flat surface, the cushion section C may be in the order of four to seven feet in length, and in the order of two and one-half to five and one-half feet in width, in which case the cushion section would contain two or more vibration transmitting members 1a and 1b, each of which is preferably separately powered by a corresponding gyroscopic motor assembly contained within the resilient roll section of the unit.

For purpose of illustration, the accompanying drawings reveal a therapeutic massage unit which provides a full-length massage mattress or massage mattress pad in the order of six to seven feet in length, and in the order of three feet to five and one-half feet in width, with the cushion section C containing two motion transmitting members 1a and 1b which are respectively powered by motor assemblies 10a and 10b respectively contained within semi-tubular and expansible housing shells 20a and 20b, detachably connected to the adjacent end of the respective motion transmitting members 1a and 1b contained in the cushion section.

Each of the motion transmitting members 1a and 1b may be formed from a lattice work of relatively thin and flexible spring steel bands formed by three or more longitudinally extending bands 2 which extend substantially the full length of the cushion section C, and which are joined by an upper transverse band 3 and a lower transverse band 4 secured as by weldments to the terminal ends of the longitudinally extending bands 2 and extending substantially at right angles thereto, as shown in FIG. 4. Where the cushion section C is made of mattress length, the longitudinally extending bands 2 are also preferably joined as by weldments to a plurality of intermediate transverse bands 5 which are inclined at an angle in the order of approximately forty-five degrees to the longitudinal bands 2 to which they are secured. It has been found that by so inclining the intermediate bands 5, more effective motion transmission is achieved at the surface of the cushion section, particularly where the cushion section is of mattress length.

The longitudinal bands 2, upper and lower transverse bands 3 and 4, and the intermediate inclined bands 5, are preferably made of a highly resilient metal such as spring steel, with each band having a thickness of one ninety-sixth to one-sixteenth of an inch, and a width in the order of one-half to one inch. As thus constructed, each of the motion transmitting members or grids 1a and 1b is bendable and flexible in a direction normal to the plane thereof but is relatively inflexible in a direction parallel to the plane thereof. It will be appreciated, however, that the motion transmitting members 1a and 1b can be formed as a lattice work composed of highly resilient and flexible bands made of plastic resins or other materials. The motion transmitting member or members 1a and/or 1b may also be made as a relatively thin layer of wax-impregnated textile belting, or from a relatively firm sheet of natural or synthetic rubber of the desired flexibility and motion transmitting characteristics.

Where two or more motion transmitting members 1a and 1b are employed as shown in FIG. 4, the adjacent members are preferably joined by a series of spaced flexible connecting straps 6 which may be formed from natural or synthetic rubber impregnated fabric or belting material, whose ends are attached as by securing screws 6' to the adjacent longitudinal bands 2, or to the adjacent side edges of the adjacent motion transmitting members. As thus connected, each of the motion transmitting members 1a and 1b may be independently vibrated, with the variable speed gyroscopic motors 10 adjusted to operate at the same or different speeds, to thereby produce a number of different massage effects at the body supporting surface of the cushion section C and the roll section R, as attained by corresponding speed adjustments of the variable speed motors 10.

The motion transmitting member or members 1a and/or 1b are compactly sandwiched between a pair of highly resilient cushioning slabs 7-7 positioned on opposite sides thereof and preferably adhesively bonded to the motion transmitting members 1a and 1b and to each other. Each of the cushioning slabs 7-7 may be in the order of one to three inches in thickness, and is preferably made from foamed natural rubber latex or synthetic rubber having high resiliency characteristics and highly compressible, but which will nevertheless immediately return to normal expanded condition when pressure is removed therefrom. The resilient cushioning slabs 7-7 are sized so that the upper ends 7' thereof will overlap the upper cross bands 3, with the lower end 7" thereof extending beyond the lower cross bands 4 for a distance of two to four inches, and with the side edges 7''' thereof overlapping the outer side edges of the adjacent motion transmitting members 1a and 1b for a distance of one and one-half to three inches. The motion transmitting members 1a and 1b are thus fully contained within and sandwiched between the cushioning slabs 7-7, and extend over the major area thereof as indicated in FIG. 4.

Each of the gyroscopic motor assemblies 10a and/or 10b as contained within the roll section R of the therapeutic massage unit includes a variable speed gyroscopic motor 10 having a speed range in the order of fifteen hundred to thirty-six hundred r.p.m., and which is so constructed that the rotative speed thereof can be accurately controlled. Each gyroscopic motor 10 is contained within the tubular motor casing 11 whose end walls 12 are provided with ventilating holes 12' as indicated in FIGS. 3, 6 and 12. Each gyroscopic motor presents a motor shaft 13 to which the motor rotor is fixedly secured and which rotates within a stationary motor stator contained within and supported by the motor casing 11. The motor shaft 13 is supported by a pair of self-aligning and permanently lubricated bearings which are mounted on the end walls 12 of the motor.

A motor cooling fan 15 is positioned adjacent each end wall 12 of the motor and is fixed to the projecting end of the rotor shaft 13 as indicated in FIGS. 3, 5, 6 and 12. Gyroscopic motion is produced by securing unbalancing weights 16 to both projecting ends of the shaft 13. Each of these unbalancing weights 16 may comprise one or more discs or washers supported by a threaded screw 16' whose end is threaded into an attaching collar 16" fixed to the projecting end of the motor shaft. The unbalancing weights 16 are weighted and positioned to produce the desired gyroscopic motion characteristics, and the paired weight supporting screws 16' may be arranged to extend substantially in the same plane or at a radial angle to one another, in accordance with the desired gyroscopic motion to be produced. By the use of self-aligning bearings to support the motor shaft 13, and the use of unbalancing weights 16 of selected weight and arranged in substantially the same plane or at a radial angle to one another, operating in combination with the other elements and parts of the therapeutic massage units as herein disclosed, accurately controlled elliptical massage strokes are produced at the body supporting surface of the cushion section C and resilient roll section R which result in a massage action which is deeply penetrating and body relaxing in character.

The motor windings of the gyroscopic motor assemblies 10a and 10b are respectively connected to a grounding lead wire 17a and 17b and a live lead wire 18a and 18b contained within a flexible conduit section 19a and 19b as shown in FIGS. 5, 10 and 11. The ground lead wires 17a and 17b and the live lead wires 18a and 18b are made relatively short and respectively terminate in insert prongs 17'a and 17'b and insert prongs 18'a and 18'b which are detachably connected to a wiring circuit supported on a relatively thin non-conducting panel 8 contained within the upper end of the cushion section C.

The panel 8 on which the wiring circuit is seated, is

made from a relatively thin sheet of electrical insulating material such as compressed fibre and may extend transversely across all of the motion transmitting members 1a and 1b, as shown in FIGS. 5, 10 and 11, and may be from three to six inches in width, and is positioned to overlap one face of the upper cross bands 3 of all the motion transmitting members 1a and 1b.

Each of the gyratory motor assemblies 10a and 10b is respectively contained within a semi-tubular housing shell 20a and 20b which is preferably made of flexible sheet metal and presents an expansible semi-tubular body portion 21 in which the gyratory motor assembly is removably contained. Each expansible body portion 21 terminates in flange portions 22 extending laterally therefrom as shown in FIGS. 10 and 11. One of the flange portions 22 of each housing shell 20a and 20b is provided with a semi-tubular deformation 22' through which the motor lead conduit 19a or 19b may extend. Each of the gyratory motor assemblies 10a and 10b is removably pocketed within the expansible semi-tubular body portion 21 of its housing shell and is preferably supported therein by the provision of a pair of resilient motor supporting elements or rings 23 which may be made of resilient non-conducting rubber and which embrace the tubular motor casing 11 of each gyratory motor 10. The relative diameters of the semi-tubular body portion 21 and motor supporting rings 23 are such that the supporting rings are snugly embraced by the semi-tubular portion 21 when the flange portions 22 thereof are drawn together.

Where two or more gyratory motor assemblies 10a and 10b and associated housing shells 20a and 20b are employed, the adjacent ends of the semi-tubular body portions 21 are arranged in spaced relation and the intermediate space therebetween filled by a connecting tube 24 formed of sheet metal whose ends are designed to project into the adjacent ends of the tubular body portions 21 as shown in FIGS. 10 and 11. Each housing shell 20a and 20b has a longitudinal length which approximately corresponds to the width of the vibration transmitting member 1a and 1b to which it is detachably connected.

The outer ends of the semi-tubular body portions 21 of the housing shells 20a and 20b are closed by cup shaped end closures 25 each presenting a tubular flange portion 25' and an end wall portion 25" having ventilating holes 25''' therein. The tubular flange portion 25' of each cup shaped end closure 25 is designed to extend into the outer end of the semi-tubular body portion 21 of its associated housing shell and to be frictionally clamped in fixed position therein when the flange portions 22 of its tubular shell are drawn together.

The flange portions 22 of each of the housing shells 20a and 20b are designed to be detachably secured to the adjacent end of its associated motion transmitting member 1a or 1b as indicated more particularly in FIGS. 6, 7, 12 and 13. The securing means illustrated in FIGS. 6 and 7 comprise a series of spaced Tinnerman nuts 26, each designed to be telescoped over one of the flange portions 22 of its housing shell, with the screw receiving hole 26' therein placed in alignment with the corresponding aligned screw receiving holes 22" formed in the flange portions 22 of the housing shell. The upper transverse band 3 of each motion transmitting member 1a and 1b, and the non-conducting wiring circuit supporting panel 8 extending thereover, are also provided with a series of spaced screw receiving holes 3', each of which is designed to receive a threaded screw 27 which is projected through the aligned holes 22" in the shell flange portions 22, as aligned with the corresponding holes 3' in the adjacent upper transverse band 3 of the motion transmitting member and the adjacent hole 26' in the Tinnerman nut 26.

The threads of each screw 27 are designed to engage the nut forming deformation 26" in one of the legs of the Tinnerman nut 26. By a proper manipulation of the securing screw 27, the shell flange portions 22 may be

drawn together to thereby contract the semi-tubular body portion 21 of the shell housing in snug embracing relation around the supporting rings 23 of the gyratory motor assembly therein, and which clamping action also draws the semi-tubular body portion 21 of the housing shell snugly around and in frictional contact with the tubular flange portion 25' of the end closure cup 25 to thereby removably retain the end closure cup in assembled relation. By removing the securing screws 27, the end closure cup 25 as well as the gyratory motor assembly can be readily removed through the outer end of the housing shell, since the ground lead wires 17a and 17b and the live lead wires 18a and 18b of the motor assemblies 10a and 10b are also readily detachable from the wiring circuit as hereinafter described.

The flange portions 22 of the motor supporting housing shells 20a and 20b may also be secured to the upper ends of the motion transmitting members 1a and 1b by alternate connecting means as indicated in FIGS. 10, 11 and 12, and wherein the Tinnerman nuts 26 are telescoped over the upper transverse bands 3 of the motion transmitting members 1a and 1b and the associated non-conducting panel 8, with the screw receiving hole 26' of each Tinnerman nut in alignment with the corresponding receiving hole 3' in the upper transverse band 3 and non-conductor panel 8. In this arrangement, each securing screw 27 is first inserted through the screw hole 22" in only one of the shell flange portions 22, thence through the hole 26' in the Tinnerman nut 26, the hole 3' in the transverse band 3 and non-conductor panel 8, and the screw threads then turned into engagement with the nut forming deformations 26" of the Tinnerman nut 26.

In this arrangement, it will be seen that one of the shell flange portions 22 may be more or less permanently secured to the motion transmitting member, thereby permitting removal and replacement of the end closure cup 25 and gyratory motor assembly when the companion flange portion 22 of the housing shell is released. When the motor assembly and closure cup are replaced, they can be held in fixed position by telescoping the aligned holes 22" in the other shell flange portion 22 over the projecting ends of the screws 27, and then applying a wing nut 28 to each screw which can be manipulated to draw both flange portions 22 together to thereby clamp the end cups and gyratory motor assembly within the semi-tubular body section 21 of the housing shell.

The housing shells 20a and 20b and connecting tube 24 are enclosed by a highly resilient arcuate shaped slab 29 formed from foamed rubber latex or synthetic rubber and whose longitudinal edges 29' extend substantially in abutting relation to the flange portions 22 of the housing shells contained therein as shown in FIGS. 7 and 13. The outer arcuate ends 29" of the arcuate cushioning slab 29 extend to or slightly beyond the outer ends of the housing shells 20a and 20b, as shown in FIG. 9. The arcuate cushioning slab 29 may be made in the order of one-half to one and one-half inches in thickness, and provides a resilient support for the feet, neck or head which may rest thereon when the therapeutic massage unit is in use.

The wiring circuits for the gyratory motor assemblies 10a and 10b may comprise a common power input cable 30 as shown in FIGS. 1 and 5 which may extend through one of the end closure cups and into the adjacent end of the cushion section C. The power input cable 30 contains a common ground wire 31 and a main live wire for each of the gyratory motor assemblies. Two such live wires 32 and 33 being provided where two gyratory motor assemblies 10a and 10b are used. The common ground wire 31 terminates in a pair of connector sockets 31a and 31b supported upon the non-conducting panel 8. The connector socket 31a is designed to detachably receive the terminal insert prong 17a' of the ground lead wire 17a extending from the gyratory motor 10a. The companion connector socket 31b is designed to receive the insert prong 34' of a ground connecting wire 34 supported by

the non-conducting panel 8 and whose other end terminates in a connector socket 34b positioned adjacent the other motor assembly 10b. The insert prong 17b' connected to the ground lead wire 17b extending from the motor assembly 10b, is designed to be detachably inserted into the connector socket 34b.

The main live wire 32 which supplies live current to the motor assembly 10a terminates in a connector socket 32a designed to receive the insert prong 18a' at the terminal end of the live lead wire 18a which extends from the motor assembly 10a. The other main live wire 33, supported by the non-conducting panel 8, terminates in a connector socket 33b designed to receive the insert prong 18b' connected to the live wire 18b which supplies current to the motor assembly 10b.

The double connector sockets 31a and 31b and associated insert prongs 17a' and 34' are insulated and protected by a tubular insulating sleeve 35a which may be slidably telescoped thereover as indicated in FIGS. 5, 10 and 11. The connector socket 34b and associated insert prongs 17b' are also electrically insulated and protected by a tubular non-conducting sleeve 35b which is slidably telescoped thereover. The connector socket 32a and associated insert prong 18a' are insulated and protected by non-conducting slidable sleeve 36a, and the connector socket 33b and associated insert prongs 18b' are similarly protected by a non-conducting slidable sleeve 36b.

It will thus be seen that the ground lead wires 17a and 17b and the live lead wires 18a and 18b which supply the operating current to the gyroscopic motor assemblies 10a and 10b may be readily and easily detachably connected to the power input circuit which is positioned directly adjacent the motor assemblies and readily accessible in the manner hereinafter described. The power input cable 30 and the common ground wire 31 and the main live wires 32 and 33 contained therein, are joined in circuit to a speed control box 37 containing a speed control rheostat or devices 37a or 37b for each of the gyroscopic motors 10, and each of which presents an exposed knob by which the motor speed may be manually adjusted. The motor speed control devices 37a and 37b in the control box 37 are supplied with current by a power cable 38 which terminates in a power source inserting plug 38'. The gyroscopic motor assemblies 10a and 10b are preferably designed to operate on either direct or alternating current, with their rotative speeds sensitively adjustable by a corresponding manipulation of the speed control devices 37a and 37b.

The cushioning slabs 7-7 which form a part of the cushion section C and the arcuate cushioning slab 29 which forms a part of the roll section R, are fully enclosed within a covering envelope 40 which presents a leg portion 40c and a hood portion 40r. The leg portion 40c compactly encloses the cushioning slabs 7-7 and the motion transmitting member or members 1a and 1b as sandwiched therebetween. The hood portion 40r is designed to enclose and embrace the arcuate cushioning slab 29 to provide a finished covering therefor. The leg portion 40c and hood portion 40r may be formed of the same covering material such as attractively patterned heavy woven cloth, or natural or artificial upholstery leathers or plastic covering materials.

The leg portion 40c of the covering envelope presents opposite facing panels 41 stitched to a pair of side strips 42 and an end strip 43 to provide corner forming welts or bead formations 44. The leg portion 40c of the covering envelope as thus formed, provides a covering sleeve which may be drawn over the bottom end 7" of the cushioning slabs 7-7 and is of sufficient length to extend to the longitudinal edges 29' of the arcuate cushioning slab 29 at the other end of the cushion section. The leg portion 40c of the covering envelope as thus formed is snugly fitted to slightly compress the cushioning slabs 7-7 and maintain the same in firm motion transmitting contact

75 with the motion transmitting member or members 1a or 1b as sandwiched therebetween.

The hood portion 40r of the covering envelope 40 presents an arcuate shaped covering panel 45 which may be either sewn to or made integral with one of the facing panels 41 of the leg portion 40c and is of sufficient area to fully cover the arcuate cushioning slab 29 and extend over the ends 29" thereof. Each of the arcuate shaped ends of the arcuate covering panel 45 is sewn to the adjacent semi-circular edge of an end panel 46 to provide a semi-circular welt or beading 47 at the ends of the roll section R. Each end covering panel 46 is provided with a circular hole therein which is defined by the inturned rim forming edges 46' of the end panel 46 as shown in FIGS. 2 and 9. The hole as thus defined is of sufficient size to expose the ventilating holes 25" in the adjacent end closure cup 25. It will be noted that the lower edge of the end covering panels 46 are square cut and in alignment with the longitudinal lower edge of the arcuate covering panel 45.

20 As shown in FIGS. 7, 9, and 13, the longitudinal lower edges of the arcuate covering panel 45 and end panels 46 are defined by double ply terminal flaps 48 as formed by inturned edge portions 48' of the covering material. 25 One side 50' of a slide fastener tape 50 is stitched to the inner edge of the inturned portion 48' of the arcuate panel 45 and end panels 46, with the other side 50" of the slide fastener tape 50 secured to the adjacent upper edge of one of the facing panels 41 and adjacent upper ends of the side strips 42 of the leg portion 40c of the covering envelope. The slide fastener tape thus extends from one of the facing panels 41, around the upper ends of the side strips 42 and across the upper end of the other facing panel 41 of the leg portion of 30 the covering envelope, with their track sections connected by a fastener slide 51.

35 As thus constructed, it will be noted that the hood portion 40r of the covering envelope provides a covering hide for the roll section which can be slipped over the arcuate cushioning slab 29 of the roll section when the leg portion 40c of the covering envelope has been fully applied to the cushioning slabs 7-7 of the cushion section of the unit. By drawing the fastener slide 51 across the full length of the track forming sections 50' and 50" of the slide fastener tape 50, the entire perimeter of the hood portion 40r can be fully secured to the upper perimeter of the leg portion 40c, so that the covering envelope provides a complete covering for the unit. It will also be noted that the double ply flap portions 48 extending from the lower longitudinal edges of the arcuate panel 45 and end panels 46 are of sufficient length to overlap the slide fastener tape 50 to fully cover the same, and so that the slide fastener tape 50 and its fastener slide 51 are substantially invisible when the unit is in use. However, these double ply flaps 48 may be bent over as shown in FIG. 8 to fully expose the fastener slide 51 for manipulation.

40 By manipulating the fastener slide 51 to open position, the lower longitudinal edges of the arcuate panel 45 and end panels 46 of the hood portion may be separated from the adjacent upper ends of the side strips 42 and one of the facing panels 41 of the leg portion 40c of the covering envelope, to thereby provide a slit 45 opening as indicated in FIG. 8 which exposes the upper end of the adjacent cushioning slab 7 of the cushion section C. The upper end portion of the adjacent cushioning slab 7 can then be lifted a sufficient extent to expose the heads of the securing screws 27 of the securing means shown in FIGS. 6 and 7 so that the flange portions 22 of the adjacent housing shell may be released; or to expose the wing nuts 28 of the alternate securing means shown in FIGS. 12 and 13 so that one of the flange portions 22 of the associated housing shell may be released.

45 50 55 60 65 70 75 When one or both flange portions 22 of the housing

shell are released, the tubular portion 21 thereof will automatically expand to release the motor assembly and closure cup 25 supported thereby. The insert prongs 17a' and 18a' associated with the lead wires 17a and 18a of the motor assembly 10a can then be separated from the connector sockets 31a and 32a of the wiring circuit to permit removal and replacement of the gyratory motor assembly 10a. Where the therapeutic massage unit is equipped with a second gyratory motor assembly 10b, the open slit may be extended to render readily accessible the insert prongs 17b' and 18b' associated with the lead wires 17b and 18b of the motor assembly 10b for separation from the socket connectors 31b and 32b of the wiring circuit and thereby permit ready removal of the gyratory motor assembly 10b. A fully operative motor 10a or 10b can then be replaced, the insert prongs and connector sockets reconnected, and the flange portions 22 of the housing shell 20a or 20b re-secured to the upper ends of the motion transmitting member 1a or 1b.

The detachable means for securing the housing shells to their motion transmitting members, and for connecting and disconnecting the lead wires extending from the motor assemblies to the wiring circuit, and which are rendered readily accessible through the slit opening presented by the slide fastener positioned as above described, greatly facilitates the removal of defective gyratory motor assemblies and the replacement of new motor assemblies in a short period of time, and without skilled labor. The simple manner in which the gyratory motor assemblies may be removed and replaced, permits the replacement to be made in the field or at the home of the user, and without returning the entire therapeutic massage unit to the factory.

It will be appreciated that therapeutic massage units may be constructed in accordance with this invention to provide a massage pad of limited size and designed to be applied to only a portion of the human body, in which case only one motion transmitting member would be contained in the cushion section, and only one gyratory motor assembly and one housing shell would be contained within the roll section. The principles of this invention, however, are applicable to the manufacture of mattress size massage pads designed to support the entire length of the body, and are particularly designed to be placed on the mattress of a full sized bed, with the roll section of the unit positioned either at the foot of the bed or at the head of the bed, as preferred by the user.

The motion transmitting system of this invention is designed to deliver elliptical massage strokes in a uniform manner to the entire body supporting surface of the cushion section and roll section of the unit. The massage motion produced at the body supporting surface of this unit is in the form of a relatively flat ellipse whose longer motion stroke extends in the longitudinal plane of the unit, and whose modulating shorter motion stroke extends vertically to the body supporting surface of the unit, as further modulated by a transverse motion stroke extending substantially parallel to but transversely of the body supporting surface of the unit.

Therapeutic massage units constructed in accordance with this invention have highly useful therapeutic effects in improving blood circulation through the muscles and joints. When the gyratory motors are adjusted to run at lower speeds in the order of fifteen to twenty-four r.p.m., the massage effect on the human body is relaxing in character and induces restful sleep. At higher speeds the massage action has an alerting effect on the body reclining thereagainst which is desirable in certain cases.

While certain novel features of this invention have been disclosed herein and are pointed out in the claims, it will be understood that various omissions, substitutions and changes may be made by those skilled in the art without departing from the spirit of this invention.

What is claimed is:

1. A therapeutic massage unit presenting a relatively

flat cushion section and a roll section at one end of said cushion section; said cushion section containing a vibration transmitting grid sandwiched between a pair of resilient cushioning slabs, said vibration transmission grid including a plurality of spaced longitudinally extending flexible metal bands joined at the ends thereof by transversely extending flexible metal bands and a series of spaced intermediate flexible metal bands inclined at an angle with respect to said end bands; said roll section containing a housing shell presenting a flexible tubular body portion, a gyratory motor removably contained in the tubular body portion of said housing shell, means for securing the tubular body portion of said shell to one end of said vibration transmitting grid and for drawing the tubular body portion thereof around said gyratory motor to provide a support therefor, a resilient cushioning slab in surrounding relation to said tubular body portion; and a covering envelope snugly enclosing said cushion section and said roll section.

2. A therapeutic massage unit presenting a relatively flat cushion section and a roll section at one end of said cushion section; said cushion section including a plurality of vibration transmitting members positioned in side by side relation and sandwiched between a pair of resilient cushioning slabs, and a series of spaced flexible connector elements joining the adjacent side edges of adjacent vibration transmitting members; said roll section containing a housing shell for each of said vibration transmitting members, each of said housing shells presenting a flexible semi-tubular body portion and a pair of spaced longitudinally extending edge portions, a gyratory motor removably contained in the semi-tubular body portion of each of said housing shells, means for securing one longitudinal edge portion of each of said housing shells to the adjacent vibration transmitting member and means for detachably securing the other longitudinal edge portion to said first named longitudinal edge portion and for drawing the semi-tubular body portion thereof around the gyratory motor contained therein to provide a support therefor; and a covering envelope snugly enclosing said cushion section and roll section.

3. A therapeutic massage unit presenting a relatively flat cushion section and a roll section at one end of said cushion section; said cushion section including a plurality of vibration transmitting grids sandwiched between a pair of resilient cushioning slabs, each of said vibration transmitting grids including a plurality of spaced longitudinally extending flexible metal bands joined at the ends thereof by transversely extending flexible metal bands and a series of spaced intermediate flexible metal bands inclined at an angle with respect to said end bands, and a series of spaced flexible connector elements joining the adjacent side edges of adjacent vibration transmitting grids; said roll section containing a housing shell for each of said vibration transmitting grids, each of said housing shells presenting a flexible tubular body portion terminating in laterally extending flange portions, a gyratory motor removably contained in the tubular body portion of each of said housing shells, means for securing the flange portions of each of said housing shells to the adjacent vibration transmitting grid and for drawing the tubular body portion thereof around the gyratory motor contained therein to provide a support therefor; and a covering envelope snugly enclosing said cushion section and roll section.

4. A therapeutic massage unit presenting a relatively flat cushion section and a roll section at one end of said cushion section; said cushion section including a plurality of vibration transmitting members positioned in side by side relation and sandwiched between a pair of resilient cushioning slabs, and a series of spaced flexible connector elements joining the adjacent side edges of adjacent vibration transmitting members; said roll section containing a housing shell for each of said vibration transmitting members, each of said housing shells presenting

a flexible semi-tubular body portion terminating in a pair of laterally extending flange portions, a gyratory motor removably contained in the semi-tubular body portion of each of said housing shells, a tubular member extending between the adjacent ends of the semi-tubular body portions of said housing shells, removable end closures for closing the outer ends of said semi-tubular body portions, means for securing one of said flange portions of each of said housing shells to the adjacent vibration transmitting member and means for detachably securing the other flange portion to said first named flange portion and for drawing the semi-tubular body portion thereof around the gyratory motor contained therein to provide a support therefor; and a covering envelope snugly enclosing said cushion section and roll section.

5. A therapeutic massage unit presenting a relatively flat cushion section and a roll section at one end of said cushion section; said cushion section including a plurality of vibration transmitting members positioned in side by side relation and sandwiched between a pair of resilient cushioning slabs; said roll section containing a housing shell for each of said vibration transmitting members, each of said housing shells presenting a flexible semi-tubular body portion terminating in a pair of laterally 20 extending flange portions, a gyratory motor removably contained in the semi-tubular body portion of each of said housing shells, means for securing one of the flange portions of each of said housing shells to the adjacent vibration transmitting member and means for detachably 25 securing the companion flange portion to said first named flange portion and for drawing the semi-tubular body portion thereof around the gyratory motor contained therein to provide a support therefor, and a covering envelope including a sleeve portion snugly enclosing said cushion section and a hood portion snugly enclosing said roll section, a slit opening adjacent said detachable flange securing means and positioned between said sleeve portion and hood portion providing convenient access to said 30 detachable flange securing means which permits convenient removal and replacement of the gyratory motor from and to the flexible semi-tubular body portion of its housing shell, and a slide fastener for closing said opening.

6. A therapeutic massage unit presenting a relatively flat cushion section and a roll section at one end of said cushion section; said cushion section including a plurality of vibration transmitting grids sandwiched between a pair of resilient cushioning slabs, each of said vibration transmitting grids including a plurality of spaced longitudinally extending flexible metal bands joined at the ends thereof by transversely extending flexible metal bands and a series of spaced intermediate flexible metal bands inclined at an angle with respect to said end bands, and a series of spaced flexible connector elements joining the adjacent side edges of adjacent vibration transmitting grids; said roll section containing a housing shell for each of said vibration transmitting grids, each of said housing shells presenting a flexible tubular body portion terminating in laterally extending flange portions, a gyratory motor removably contained in the tubular body portion of each of said housing shells, a tubular member extending between the adjacent ends of the tubular body portions of said housing shells, an end closure for closing the outer ends of said tubular body portions, each of said end closures presenting an end wall having ventilating holes therein, means for detachably securing the flange portions of each of said housing shells to the adjacent vibration transmitting grid and for drawing the tubular body portion thereof around the gyratory motor contained therein to provide a support therefor; and a covering envelope including a sleeve portion snugly enclosing said cushion section and a hood portion snugly enclosing said roll section, a slit opening between said sleeve portion and hood portion providing access to said detachable

securing means, and a slide fastener for closing said opening.

7. A therapeutic massage unit presenting a relatively flat cushion section and a roll section at one end of said cushion section; said cushion section containing a plurality of vibration transmitting members sandwiched between a pair of resilient cushioning slabs; said roll section containing a housing shell for each of said vibration transmitting members, each of said housing shells presenting a flexible tubular body portion, a variable speed gyratory motor removably contained in the tubular body portion of each housing shell, means for detachably securing each housing shell to one end of its vibration transmitting member whereby the tubular body portion may be flexibly drawn into supporting relationship around the gyratory motor contained therein, and an arcuate cushioning slab in surrounding relation to the tubular body portions of said housing shells; a wiring circuit which includes lead wires extending from each of said gyratory motors through its supporting shell and designed to project into the adjacent end of the cushion section, current input wires extending through an outer end of one of said housing shells, separable terminal prongs and socket connectors associated with the terminal ends of said motor lead wires and said current input wires and pocketed within the adjacent end of said cushion section, and speed control means connected to said current input wires and positioned externally of said cushion section for independently controlling the rotative speed of said motors; and a covering envelope including a sleeve portion enclosing said cushion section and a hood portion enclosing said roll section, a slit opening between said sleeve portion and hood portion and positioned adjacent said detachable shell securing means and said terminal prongs and socket connectors and providing convenient access thereto and whereby said flexible tubular body portion of the housing shell may be expanded and contracted and said motor lead wires disconnected and reconnected to said wiring circuit in a manner to permit convenient removal and operative replacement of each of said gyratory motors from and to their respective housing shells, and a slide fastener for closing said opening.

8. A therapeutic massage unit presenting a relatively flat cushion section and a roll section at one end of said cushion section; said cushion section containing a plurality of vibration transmitting grids positioned in side by side relation and sandwiched between a pair of resilient cushioning slabs, and means for flexibly connecting said grids along adjacent side edges thereof; said roll section containing a housing shell for each of said vibration transmitting grids, each of said housing shells presenting a flexible tubular body portion terminating in a pair of laterally extending flange portions, a gyratory motor removably contained in the tubular body portion of each housing shell, means for securing one of the flange portions of each housing shell to one end of its vibration transmitting grid and means for detachably securing the other flange portion to said first named flange portion and for drawing said flange portions together whereby the tubular body portion provides a support for the gyratory motor contained therein, and an arcuate cushioning slab secured in surrounding relation to the tubular body portions of said housing shells; a wiring circuit which includes lead wires extending from each of said gyratory motors through its supporting shell and designed to project into the adjacent end of the cushion section, current input wires extending through an outer end of one of said housing shells, separable terminal prongs and socket connectors associated with the terminal ends of said motor lead wires and said current input wires and pocketed within the adjacent end of said cushion section, and speed control means connected to said current input wires and positioned externally of said cushion section for independently controlling the rotative speed of said motors; and a covering envelope including a sleeve portion enclosing

said cushion section and a hood portion enclosing said roll section, a slit opening positioned adjacent said detachable flange securing means and between said sleeve portion and hood portion providing access to said detachable securing means, terminal prongs and socket connectors which permits convenient removal and operative replacement of the gyratory motors from and to the tubular body portion of their respective housing shells, and a slide fastener for closing said opening.

9. A therapeutic massage unit presenting a relatively flat cushion section and a roll section at one end of said cushion section; said cushion section containing a plurality of vibration transmitting grids positioned in side by side relation and sandwiched between a pair of resilient cushioning slab means for flexibly connecting said grids along the adjacent side edges thereof, and an insulating panel positioned between said cushioning slabs and adjacent one end of said vibration transmitting grids; said roll section containing a housing shell for each of said motion transmitting grids, a tubular member extending between the adjacent ends of said housing shells, each of said housing shells presenting a flexible semi-tubular body portion terminating in a pair of laterally extending flange portions, a variable speed gyratory motor removably contained in the semi-tubular body portion of each housing shell, means for detachably securing the flange portions of each housing shell to one end of its vibration transmitting grid and for drawing said flange portions together whereby the tubular body portion thereof provides a support for the gyratory motor contained therein, and an arcuate cushioning slab in surrounding relation to said semi-tubular body portions and intermediate tubular

member; a wiring circuit which includes lead wires extending from each of said gyratory motors through its housing shell and designed to project into the adjacent end of the cushion section, current input wires extending through an outer end of one of said housing shells, separable terminal prongs and socket connectors associated with the terminal ends of said motor lead wires and said current input wires positioned on said insulating panel and pocketed within the adjacent end of said cushion section, and speed control means connected to said current input wires and positioned externally of said cushion assembly for independently controlling the rotated speed of each motor; and a covering envelope including a sleeve portion enclosing said cushion section and a hood portion enclosing said roll section, a slit opening between said sleeve portion and hood portion positioned adjacent said detachable flange securing means and providing convenient access to said detachable flange securing means, terminal prongs and socket connectors which permits convenient removal and operative replacement of the gyratory motors from and to the tubular body portions of their respective housing shells.
